ELECTRIC SWITCH

Herman J. Hammerly, Plainville, Conn., assignor
to The Trumbull Electric Manufacturing Company, Plainville, Conn., a corporation of Connecticut

Application December 6, 1939, Serial No. 307,766

9 Claims. (Cl. 200—133)

My invention relates particularly to what are commonly termed polyphase entrance switches.

One object is to provide a construction of this character which is convenient for wiring at either end; that is, so that the line and load connections may be brought in or out either at the top or bottom with a maximum of convenience.

In installing entrance switches it is frequently necessary to utilize a previously installed wiring system where the line and load wires may be found in various locations. To facilitate connecting the entrance switch it is desirable that the line and load terminals be arranged so as to require a minimum alteration in the location of the wires and a minimum amount of cutting, splicing, bending, etc. As it is usually impossible to know in advance what the arrangement of wires may be in a given installation, it is desirable that the switch itself be so constructed as to permit convenient connections by simple re-arrangement of the parts of the switch or fuse mechanism.

In carrying out the invention, I have devised an arrangement utilizing switch and fuse units which are themselves more or less conventional but are so constructed and arranged that by reversing the position of the fuse unit with respect to the switch unit I have made it possible to wire line terminals from the top or bottom of the switch box and wire the load terminals from the top or bottom without requiring any substantial bending, twisting or crossing of the wires.

In the drawings, Fig. 1 is a front view of a switch construction embodying one form of my invention, the cover of the box being shown open and the switch mechanism and actuating parts being shown in the closed circuit or open position.

Fig. 2 is a front view of the box with the cover closed.

Fig. 3 is a side view of the same.

Fig. 4 is a detail view of the insulating barrier used between the switch and fuse units.

Fig. 4a is a perspective view of part of the device for preventing access to the fuses when the circuit is closed and the cover is sealed.

Fig. 5 is a horizontal sectional view of the construction showing the cover closed, the section being taken partially on the plane of the line 5—5 of Fig. 1.

Fig. 6 is a vertical sectional view on the plane of the line 6—6 of Fig. 1, the cover of the box being closed.

Fig. 7 is a rear view of the fuse unit and connecting bars with the fuse block in the position of Fig. 1, parts being broken away to show details of construction.

Fig. 8 is a front view of the fuse unit and con-

nected bars with the block and connecting bars reversed.

Fig. 9 is a diagrammatic front view of the switch and fuse units showing the switch unit 5 with the line connections brought in from the bottom and the load connections leading out at the top.

Fig. 10 is a similar diagrammatic view with the line connections leading in from the top and the load connections brought out at the bottom.

Fig. 11 is a side view and vertical section of the switch and fuse units showing the line and load connections all arranged at the top.

Fig. 12 is a similar view showing the line and load connections all arranged at the bottom.

The box 14 contains the switch and fuse mechanism and is provided with a cover 15 hinged at 16 along one edge and provided with a catch 17 at the other edge.

The switch mechanism per se consists preferably of a number of separate units each having an insulating block 18 and fuse or protective units on an insulating block 19. These are arranged in the box in such a position that when the cover is closed the fuse units only may be made accessible through an opening 20 which is normally covered by a sliding door 21. This door is supported in guide brackets 22 and provided with an external handle 23.

The interior of the box is in effect divided into a switch chamber and a fuse chamber by means of an insulating barrier plate 24 which is mounted between the switch and fuse units.

The box itself is provided with any suitable number of knockouts 25 arranged in any desirable number of convenient positions.

The switch blocks 18 are mounted on brackets 26, 26 which are secured in the bottom of the box. The blocks may be secured in any suitable manner as for instance by screws 26'.

In the form of switch unit herein disclosed, each switch unit has contact members 27 and 28 between which a movable switch member 29 is adapted to be interposed. This switch member is carried by an insulating slide 30 actuated in any suitable manner. Between adjacent switch units I preferably provide insulating barrier plates 31 for separating the parts of opposite polarity. These plates may be secured in any suitable manner.

In the form shown the switch members are actuated by a crank shaft 32 mounted in the sides of the box and having an external handle 33 which may be guarded by a member 34.

Inside the box is mounted a slide 35 which is guided by a pin 36 and connected at its lower end to the crank shaft 32. The upper end of this slide is provided with an offset 37 which is adapted to stand in the line of movement of

the projection 38 carried by the sliding door 21 of the cover.

When the switch is in the "on" or closed circuit position, the projection 31 stands in the path of movement of the projection 38 so that the door 21 cannot be opened when the cover 15 is closed. It is necessary to externally open the cover or open the switch before access may be had to the fuses through the doorway 20.

The fuse block 19 is supported by one or more brackets 40 mounted in the bottom of the box. The block is removably secured preferably by a number of screws 41 passing through openings 41'. This fuse block carries the fuse clips 42 and 43 for the conventional circuit protecting 15 fuses or relays.

A bar 44 serves to connect each switch unit with the corresponding fuse unit. The upper end of the bar 44 is suitably secured to a switch unit, for instance by a screw or stud 45 and a nut 46. The lower end of the bar 44 is removably connected by a screw 48 to a plate 49 which is suitably connected to the fuse clip 43 by means of a screw 50, or other means.

The central part of the insulating base 19 is 25 provided with a passage 51 through which the lower offset end of the bar 44 is extended so as to removably connect it with the plate 49 as above described.

Each of the switch units is provided with a 30 binding post or line terminal 52 which is connected to the adjacent switch contact 27. Fuse clip 42 of each fuse unit is provided with a load terminal 53 arranged at one edge of the insulating base 19.

The construction shown provides for a three 35 wire switch control. The fourth wire or wires may be connected to the terminal 54 or 55 and these terminals may be mounted on an insulating block 55' secured to the side of the box and they may be grounded through a strap 56 connected to the box if desired.

The insulating barrier 24 is preferably provided with slots 57 to allow for the passage of 45 the connector bars 44 previously described. The barrier is thus supported on the bars which prevent movement of the barrier transverse of the box. The insulating barrier is also preferably provided with a number of holes to permit the 50 passage of the line wires when the line wires are to be led out from the bottom of the switch. In view of the fact that the fuse block is in effect offset laterally with respect to the switch units, the left hand line terminal 52 can be 55 readily reached from either the upper or lower side without having to pass through the barrier plate 24. When the line wires are led out through the bottom the other two line wires will pass down through the openings 58, 58 in the barrier 24. The barrier plate 24 is also provided with passages 59 to accommodate the load wires when they are led out through the top as would be the case in the arrangements shown in Figs. 1, 9 and 11. In the arrangements shown in Figs. 9 and 12, the line wires are led in from the 60 bottom.

To facilitate bringing the line wires in from the bottom, I preferably provide the fuse block with grooves 60, 60 and 61, 61.

As previously indicated the arrangement in Fig. 1 is for convenience in wiring the line wires and load wires from the top or upper part of the box or wiring the line terminals from the bottom. In case it is desired to wire the load 70 terminals from the bottom it is merely neces-

sary to demount the insulating block 19 by removing screws 41 and the screws 48 which connect the bars 44 and the plates 49. The insulating block 19 is then inverted so as to bring the load terminals 53 at the bottom edge of the block and in the lower part of the box. The bars 44 will then again be attached by the screws 48 to the plates 49 and the screws 41 are replaced to give mechanical support to the block. This brings all of the load connections in the lower part of the box whereupon the load wires may be attached.

For convenience in assembly, the ends of screws 41 and 48 are made pointed. It is also preferred that all of the screws such as 41 and 48 be made of the same size so that they are interchangeable.

To facilitate the wiring I have preferably arranged all of the line terminals 52 on a lower level from the load terminals 53. The line terminals are usually wired first and the load terminals can then be wired without interfering with the line terminals. It will be seen that in this construction there is no necessity of having load wires cross the line wires.

The word "Line" is placed on the blocks 18 as shown to indicate the terminals for the line connections. The word "Load" is placed on the edge of the fuse block 19 to indicate the terminals for the load connections no matter how the block is positioned.

Obviously, in this construction, the number of poles may be increased indefinitely, or may be decreased.

So that the block may be used in either of its positions without trouble, the holes for the screws 41 and 48 are preferably located on the horizontal center line of the fuse block, and the fuse clips at the edges of the block are located at equal distances from this center line.

I claim:

1. In an electric switch combination, a switch unit having a line terminal, a separately formed, reversible fuse unit having a load terminal, common means for securing said fuse unit in position in either of two wiring positions, a detachable connection between said units effective in either of said positions and an insulating barrier plate mounted between said units and having a passage for a conductor.

2. In an electric switch combination, a switch unit having a line terminal, a separately formed, reversible fuse unit having a load terminal, common means for securing said fuse unit in position in either of two wiring positions, a detachable connection between said units effective in either of said positions and an insulating barrier plate mounted between said units and having passages for line and load wires.

3. The combination of a row of switch units each having a line terminal at one side and a fuse connection at its opposite side, a discrete reversible fuse block having a pair of fuse clips, one clip of each pair having a load terminal at one edge of the fuse block and the other clip of each pair having a connector plate extending toward the first clip, a connector bar beneath the block removably connecting each connector plate with one of the fuse connections in either of two wiring positions of said fuse block and single means for supporting said fuse block independently of the switch units in either of said two positions.

4. In a polyphase entrance switch, a plurality of switch units, means for supporting said units

side by side, each unit having a line terminal at the front and a load terminal, a reversible fuse-carrying block, removable means for supporting said block along its center line independently of the switch units, said block having a pair of fuse clips corresponding with each switch unit, a load terminal directly associated with one of the clips of each pair of clips at the front of one edge of the block, an extension plate connected to the other of each pair of clips and extending midway between the clips, connecting bars at the rear of the block detachably connected at one end of each to the respective load terminals of the switch units, and means accessible at the front of the block for detachably connecting the other end of each of the rear bars with one of the extension plates midway between the clips of the respective pairs of clips.

5. A reversible fuse-carrying block of insulating material, a plurality of fuse-receiving clips secured to the front of the block adjacent each of the upper and lower edges thereof and arranged in pairs, a wire receiving terminal directly connected electrically and mechanically to each of the clips immediately adjacent one edge of the block at the front thereof, said block having a passage extending through it from front to back approximately midway between the clips of each pair, a front conducting plate connected at the front of the block to each of the fuse clips opposite one of those to which a wire receiving terminal is connected, a conducting bar at the back of the block in rear of each of the front plates, means accessible at the front of the block for connecting each front plate to one end of the back bar in its rear through one of the passages, the other end of each back bar extending beyond one of the edges of the block for connection with a switch member, switch mechanism supported independently of the fuse carrying block and means for supporting said fuse carrying block in either of two positions for wiring, said block being reversible when the bars and plates are disconnected.

6. In a polyphase switch the combination of a switch unit including an insulating base with a passage extending from front to rear, a switch contact at each side of the passage, a switch member movable in the passage between the contacts, a line terminal connected to one contact and accessible from the front of the base, a discrete fuse carrying block, fuse clips mounted near the upper and lower edges at the front of the fuse carrying block, a load terminal carried by one edge of said block and connected to the adjacent clip, said latter block having a passage substantially midway between said clips, a connecting strap attached to the opposite clip at the front of said block and extending between the clips, a second connecting strap attached at one end to the second switch contact, means for detachably connecting the opposite end of said second strap to the front strap at said passage in the fuse block, means for supporting the switch base and means connected at substantially equal distances from its edges for supporting the same adjacent the switch base, said fuse block being reversible.

7. The combination of a switch unit including an insulated base with laterally spaced switch contacts, a switch member movable to connect the contacts, a line terminal connected to one

contact and accessible from the front of the base, and a fuse carrying block having fuse clips mounted at the front near its upper and lower edges, a load terminal carried by one edge of said block and connected to the adjacent clip, said latter block having a transverse passage between said clips, a connecting strap attached to the opposite clip at the front of said block, a second connecting strap attached at one end to the second switch contact, means for detachably connecting the opposite end of said second strap to the front strap at said passage in the fuse block, means for supporting the switch base, means for reversibly supporting the fuse block adjacent the switch base, and an insulating barrier plate mounted between the switch unit and the fuse block and having passages for line and load conductors.

8. The combination of a switch unit including an insulating base with laterally spaced switch contacts at the front, a switch member movable to connect said contacts, a line terminal connected to one contact and accessible from the front of the base, a fuse carrying block, fuse clips mounted near the upper and lower edges at the front of the fuse carrying block, a load terminal carried by said block adjacent one clip, said block having a passage between said clips, a connecting strap attached to the opposite clip at the front of said block, a second connecting strap attached at one end to the second switch contact, means for detachably connecting the opposite end of said second strap to the front strap at said passage in the fuse block, means for supporting the switch base and means for supporting the fuse block adjacent the switch base, said fuse block being reversible and having grooves in its rear face alongside of said respective connecting straps for line conductors in the respective reversed positions.

9. An enclosed polyphase entrance having at least a three-pole assembly including a plurality of aligned insulating blocks, a switch unit on each block including a pair of laterally spaced stationary switch contacts and a movable contact therebetween to connect the same, a line terminal connected to one stationary contact of each pair of stationary contacts at one side of the movable contact, a reversible insulating block independently mounted below said aligned blocks, a fuse device on said reversible block for each switch unit, each fuse device including upper and lower clips for supporting a fuse, a load terminal fixed to one of said clips in vertical alignment therewith and detachable means of connection between each switch supporting block and said reversible block at the side opposite the line terminal including a bar having one end connected to one of the stationary contacts of each switch unit, means for connecting its other end detachably to the other clip of the fuse device and means for removably securing said reversible block substantially along its center line whereby when the reversible block is in operative position alongside of said switch supporting blocks in either normal or reverse position, said load terminals will be out of vertical alignment with the line terminals and with the moving parts of the switch units permitting wiring of said load terminals with a minimum of interference with the line wires.

HERMAN J. HAMMERLY.
